SPRING STRUCTURE

John M. Caughey, Adrian, Mich., assignor, by mesne assignments, to Hoover Ball and Bearing Company, Saline, Mich., a corporation of Michigan. Original application June 20, 1960, Ser. No. 37,478. Divided and this application Aug. 30, 1963, Ser. No. 305,628.

1 Claim. (Cl. 267—107)

The present invention relates to improvements in spring elements of the stringer or linear type of design especially adapted to suit the requirements of furniture manufacturers. This application is a division of my copending United States application, Serial No. 37,478, filed June 20, 1960, now abandoned.

It is an object of the invention to provide spring structure for the seats and backs of furniture which is less costly to produce than currently used coil structures yet equal the best quality coil types in comfort and durability.

Another object is to provide spring elements for the seats and backs of furniture which have inherent stability and make possible the elimination of elaborate systems of diagonal strut bracing required with conventional coil constructions.

A further object of the invention is to provide inexpensive, yet comfortable and durable spring elements which may be readily attached at one or both ends to wooden or metal frames by mere insertion of the end portions of the springs without additional securing means.

Yet another object of the invention is to provide a spring element of the type described wherein end portions of the element are in the form of inverted U-portions whereby the terminal end of the element constitutes a leg of the U-portion and may be inserted in a hole in frame structure so that the associated leg portion engages an outer surface of the frame structure, providing a resilient gripping connection between the ends of the spring element and the frame structure.

These and other objects and advantages residing in the present invention will appear from the following specification and claims.

In the drawings,

FIG. 1 is a fragmentary plan view of a davenport back frame showing a spring element in accord with the invention mounted therein, and

FIG. 2 is a side elevational view of FIG. 1.

As will be appreciated from FIGS. 1 and 2, a spring element 10 is mounted between frame portions 12 and 14 which may be part of the back of a davenport. The frame portions 12 and 14 are illustrated as being of wood and of rectangular cross section, each including an upper surface 16 and an inner planar face surface 18. The spring elements 10 (of which only one is shown in FIG. 1) which collectively make up the back spring structure, are spaced along the frames 12 and 14 with each having a linear portion 20. Opposite ends of the portion 20 merge into fishmouth portions 22 and 24, the end portions 26 and 28 of which each comprise an inverted U-shaped frame anchor portion 30. The portions 22 and 24 are defined by torsion bar portions 32, 34, 36, 38, 40, 42, and 44, with the portions 38 and 44 being integral and lateral extensions of the inner legs 46 of the portions 30 and engaging with the frames 12 and 14. The outer legs 48 of the portions 30 are received in drilled holes 50 in the frame portions 12 and 14 which intersect the frame surface 16. The frame portions 52 connect ad-

2

jacent spring elements 10 through clips 54 in a well known manner.

Preferably, the spacing of the legs 46 and 48 is such, with reference to the location of the holes 50 to the frame inner face surfaces 18, that the frame portions 12 and 14 are resiliently engaged in the bight of the anchor portions 30 formed by legs 46 and 48. In this manner an easily accomplished, yet firm, connection of the spring element end portions 26 and 28 to the frame members is produced. As the torsion bar portions 38 and 44 are transversely related to their associated anchor portion inner leg 46 and engage the frame inner face surfaces 18, lateral stability of the spring element relative to the frame is provided and the portions 30 function as hinge pins to permit the portions 38 and 44 to effectively function torsionally.

It is appreciated that other embodiments of the invention may be apparent to those skilled in the art without departing from the spirit and scope thereof, and it is intended that the invention be defined only by the scope of the following claim.

I claim:

In combination, furniture having a pair of spaced frame members to receive and support stringer-type wire spring elements, said frame members having relatively flat upper and inner face surfaces, holes defined in said frame members and opening through said upper surfaces, said holes of each frame portion lying in a plane substantially parallel to the inner face surface of the associated frame member and spaced therefrom, stringer-type wire spring elements each comprising a linear portion, fishmouth portions located at opposite ends of said linear portion to support said linear portion in spaced relation to the frame members, said fishmouth portions being defined by spaced torsion bar portions transversely disposed to said linear portions and portions disposed substantially parallel to the length of said linear portion and extending between said torsion bar portions, said fishmouth portions having frame member engaging portions in the form of frame anchor portions, said anchor portions each taking the form of an inverted U having inner and outer leg portions, said outer leg portions each adapted to be received in a frame member hole, the spacing between the leg portions of a common anchor portion being so related to the spacing between the holes of a frame member and the inner face surface thereof that said inner leg portion resiliently engages said frame inner face surface upon the associated outer leg portion being received within a frame member hole, said leg portions being disposed in a plane parallel to the longitudinal axis of said linear portion, a torsion bar portion affixed to each of said inner leg portions and transversely disposed thereto wherein said last-mentioned torsion bar portions resiliently engage said frame member upon said outer leg portions being received within a frame member hole, said leg portions being connected by arcuate portions disposed in the plane of said leg portions, said arcuate portions being out of contact with said upper surfaces.
